(57) **CLAIM**

The ornamental design for a wall panel with simulated masonry, as shown and described.

DESCRIPTION

FIG. 1 is a perspective of a wall panel with simulated masonry embodying the design of the present invention.

FIG. 2 is a front elevational view of the wall panel with simulated masonry;

FIG. 3 is a rear elevational view of the wall panel with simulated masonry;

FIG. 4 is a left side elevational view of the wall panel with simulated masonry, taken in the plane of line 4—4 in FIG. 1;

FIG. 5 is a right side elevational view of the wall panel with simulated masonry, taken in the plane of line 5—5 in FIG. 1;

FIG. 6 is a top view of the wall panel with simulated masonry, taken in the plane of line 6—6 in FIG. 2; and,

FIG. 7 is a bottom view of the wall panel with simulated masonry, taken in the plane of line 7—7 in FIG. 2.
